Inventor

J. A. Brown,

By his Attorney

Wm H. Reid.

UNITED STATES PATENT OFFICE.

JULIUS A. BROWN, OF PEEKSKILL, NEW YORK, ASSIGNOR TO ERNEST LOOMIS, OF PEEKSKILL, NEW YORK.

SPRING STYLUS MOUNTING FOR PHONOGRAHS.

Application filed July 7, 1922. Serial No. 573,425.

To all whom it may concern:

Be it known that I, JULIUS A. BROWN, a native of Austria, and who has applied for citizenship of the United States of America, and a resident of Peekskill, in the county of Westchester and State of New York, have invented certain new and useful Improvements in Spring Stylus Mountings for Phonographs, of which the following is a specification.

The object of the present invention is to provide an improved form of stylus arm mounting for a reproducer, that is constituted by a plate spring doubled sharply on itself at one portion; and a further object is to provide such a spring member in which the axis or bend of the structure will lie approximately in the plane of the diaphragm.

In the accompanying drawing showing one embodiment of my invention, Fig 1 is a front elevation.

Fig. 2 is a side elevation partly in section.

Fig. 3 is an end elevation.

Figs. 4 and 5 show the spring member detached.

Fig. 6 shows the stylus arm and attached bracket.

Fig. 7 is a partial view enlarged through the spring and stylus arm.

Figs. 8 and 9 show slight modifications of the spring plate.

The reproducer may be of the usual or conventional form, the frame 2 having the usual diaphragm 3 that is located a short distance within the outer plane of the frame. The stylus arm 4 is attached by one end to the diaphragm, and secured at its other end to a bracket 5, having an extension 6 arranged to carry the usual stylus needle 7.

A spring member denoted generally by 8 has two portions attached respectively to the bracket 5 and the frame 2. As shown this spring comprises a bottom strip portion 9, and a top strip portion 10 connected by a U-shaped portion 11, integral with both plates, that is given a rounded bend so that these plates are slightly spaced apart, see Fig. 7. The upper plate 10 is suitably secured to the bracket 5 as by soldering, and this plate may have an angular bend 12, with a slot at 12', to receive the bracket 5.

The lower plate 9 is shown provided with apertures 13, 13, for receiving screws 14,

14, to secure this bottom plate to the frame 2. The upper plate 10 extends longitudinally or in the direction of the frame, and has its extremities bent downwardly at 15 and 16 to engage the flat faces of the frame at this portion. These extremities are provided with openings such as slots 17, 18 and screws 19 and 20 passed through these slots into the frame, for the purpose of merely pressing the extremities against the frame at this portion. The plate 10 is also provided with large apertures 21, 22, above the apertures for the screws 14, to permit application and removal of these screws, that hold the lower plate on the frame.

It will thus be seen that the bracket carrying the stylus arm and needle are rigidly secured to the spring plate beyond the bent extensions, while the ends of the extensions are secured to the frame. This will produce a resilient portion that can vibrate adjacent the bend 11, which is substantially in the plane of the diaphragm 3. By this means the strain at the connection of the stylus arm with the diaphragm is substantially perpendicular to the diaphragm and will not tend to loosen the connection with the diaphragm; that is somewhat angular in other constructions and tends to extend this connection and injure the diaphragm.

In Fig. 8 I show a slight modification in which the bend corresponding to the bend 11 in the other views is given a downward curve at 23 that will increase the resiliency of the spring action. In Fig. 9 a similar modification is set forth, but the bend at 24 is given an upward curve, for the same reason.

What I claim is:

1. A stylus arm mounting, comprising a flat strip of resilient sheet metal substantially H-shaped, the middle connecting portion being bent to bring the two bar portions substantially parallel, one bar of the strip being secured to the reproducer frame, the other bar portion being secured to the stylus arm bracket at its middle part, said latter bar having slots at the end portions, and screws passed through each said slotted portion into the frame.

2. A stylus arm mounting, comprising a flat strip of resilient sheet metal substantially H-shaped, the middle connecting por-

tion being bent to bring the two bar portions substantially parallel, one bar of the strip being secured to the reproducer frame, the other bar portion being secured to the stylus
5 arm bracket at its middle part, said latter bar having slots at the end portions, and screws passed through each said slotted por-

tion into the frame, said bar portion also having a short extension on this free longitudinal edge that is reduced at the middle 10 portion.

Signed at New York, New York, on June 23d, 1922.

JULIUS A. BROWN.
